(57) **CLAIM**

We claim the ornamental design for a sheath adapter, as shown and described.

DESCRIPTION

FIG. 1 is a front side elevational view of a sheath adapter showing our new design;
FIG. 2 is a left side elevational view thereof;
FIG. 3 is a rear side elevational view thereof;
FIG. 4 is a right side elevational view thereof;
FIG. 5 is a perspective view thereof;
FIG. 6 is a top plan view thereof;
FIG. 7 is a bottom plan view thereof;
FIG. 8 is a front side elevational view of the sheath adapter of FIG. 1, shown in an environment;
FIG. 9 is a left side elevational view thereof;
FIG. 10 is a rear side elevational view thereof;
FIG. 11 is a right side elevational view thereof;
FIG. 12 is a perspective view thereof;
FIG. 13 is a top plan view thereof; and,
FIG. 14 is a bottom plan view thereof.

The broken lines immediately adjacent to the claim depict the bounds of the claimed design, while all other broken lines are directed to environment. The broken lines form no part of the claimed design.
